DEEP WELL AND CISTERNS AUTOMATIC PUMPING PLANT

Filed April 6, 1939

UNITED STATES PATENT OFFICE

2,246,678

DEEP WELL AND CISTERNS AUTOMATIC
PUMPING PLANT

Thaddeus S. Harris, Waverly, Ill.

Application April 6, 1939, Serial No. 266,314

3 Claims. (Cl. 103—5)

This invention relates to a deep well pump of the jet type, as also described in my patent application No. 223,005, filed August 4, 1938, and my later application No. 256,713, filed February 16, 1939.

Some of the advantages provided by the construction described herein are that means are provided for securing automatic cistern water service from the same pump that provides the deep well operation, and these same means can also be utilized to provide automatic repriming of the deep well unit.

Figure 1 of the accompanying drawing illustrates a diagrammatic elevation of the complete installation, with the more essential parts shown in section.

Figure 2 shows a sectional view of a slightly modified form of the main automatic valve assembly.

Figure 3 is a sectional view of an abbreviated form of the repriming valve that can be used when cistern water service is not desired.

Referring to Figure 1, a suction type force pump 1 is belted to the motor 2. From the discharge chamber 3 a discharge pipe 4 extends to the storage tank 5, with the control valve 6 connected into this line. The diaphragm chamber 7 has the diaphragm 8 across it, with the top side open to atmospheric pressure, while the lower side is subject to the pressure within the pipe 4. Diaphragm 8 is connected to valve 6 and the spring 9 is disposed to hold valve 6 closed under considerable pressure.

A second discharge line 10 extends from chamber 3 to the jet unit in the well, with valve 11 controlling this discharge line. Valve 11 is connected to the diaphragm 12 and a spring 13 is disposed to close valve 11.

An intake pipe 14 extends from the intake chamber 14' to the jet unit in the well. This passage is controlled by a check valve 24' and by valve 17 of the valve assembly unit 15.

The automatic unit 15 has the main control rod 16 with the valve 17 fixed to it and controlling port 17'. Another pipe line 18 connects into the intake end of unit 15, extending to the cistern 19 and joining passage 14 by the port 20. Port 20 is controlled by valve 20', which is slidably connected on rod 16, being supported by a sleeve 21 which is fixed on rod 16. A spring 21' is disposed to hold valve 20' against sleeve 21. Valve 20' has the cylindrical sleeve guide portion 22 with the tapered slit 23. A hand valve 24 provides for manually closing pipe 18. A pipe 25 extends from tank 5 to the unit 15, where it also joins pipe passage 14, under control of valve 20'. A hand valve 25' provides for manually closing this pipe.

The diaphragm chamber 26 is fixed to the intake portion of unit 15, with the diaphragm 16

extending across it and carrying the main control rod 16. The spring 28 is disposed to hold the rod 16 in such position that valve 20' is open. A pipe 29 extends from pipe 4 to the right side of the diaphragm chamber, and this side of the chamber has the port 30, which is controlled by valve 31, fixed on rod 16. Valve 31 has the slotted sleeve guide 32, so that the port is practically closed well before valve 31 seats. Port 30 is connected by pipe 33 to storage tank 34 with the hand valve 35.

An electric switch lever 36 is so pivoted to the diaphragm chamber casing that it may be engaged by the post 37 on diaphragm 27. A spring 31' causes the points 27, 27' to be normally closed.

The jet booster unit 38 has the jet 39 connected to pipe 10, while the delivery tube 40 is connected to pipe 14. The intake pipe 41 connects to the water of the well. The jet opening has the small cleaner rod 42 extending through it when the pump is not operating. The plunger 43 carries rod 42 and a spring 44 supports plunger 43 in cylinder 45.

Tank 5 has the pressure controlled switch 46 connected to its service line 46', and tank 34 has the switch 47 connected to its service line 47'. Switches 46, 47 are connected in multiple, in the main feed wire 48, by wires 49, 50, 51. Wires 50, 51 also connect to points 27, 27', respectively. One terminal of motor 2 is connected to the main wire 52 while the other is connected by wires 53, 53' to switches 46, 47.

Referring to Figure 2, this shows an automatic unit with practically the same form as unit 15 of Figure 1, except that the cylinder 68 and the plunger 61 replace the diaphragm chamber 26 and diaphragm 26', and the switch lever 63 is operated from the end of the main casing, to replace the lever 36 of unit 15.

Referring to Figure 3, the diaphragm chamber 65 has the diaphragm 66 to which is fixed the valve rod 67. Rod 67 extends through the packing gland 68 and has valve 69 fixed to it. Valve 69 controls port 70, which connects passages 25 and 14. A spring 71 is disposed to hold valve 69 open, when the pump is idle.

The operation of the installation shown in Figure 1 is as follows: With switches 46, 47 set on a 20 lb. to 40 lb. range, the spring 28 is adjusted so that diaphragm 66 starts to move at about 45 lbs. pressure per square inch on diaphragm. Valve 11 is set to open at about 50 lbs. pressure and valve 6 is set to commence to open at about 55 lbs. pressure, with the diaphragm completing its movement and completely closing valve 20' at about 60 lbs. pressure.

Valves 20' and 31 are at least partially open when the pump is idle, so, regardless of whether switch 47 or 46 closes, water is at first drawn

through port 20, coming from the cistern, if valves 24, 35 are open and valve 25' closed, as when providing cistern water service. Water is delivered to tank 34 until the pressure causes switch 47 to open. If switch 46 is also closed the pump continues to operate throwing the diaphragm to partially close valve 31, after which the pressure quickly increases to open valve 11, putting the jet into operation. Further increase of discharge pressure opens valve 6 and closes valve 20' which slides back on rod 16, allowing valve 31 to also close under sufficient pressure to prevent the flow of water to tank 34. The installation is then in full deep well operation. If unit 15 is to be used only for priming purposes, valves 24 and 35 are closed and valve 25' opened. The starting operation is then the same except that the first water is drawn from tank 5, providing for refilling pipes 10 and 14 to replace any leakage and insuring that full discharge pressure will quickly be built up. Should switch 47 fail to open for any reason as because of valve 36 being closed, then switch 36 breaks the circuit as the diaphragm completes its shift.

Rod 42 serves to keep the jet free of trash as it moves into the jet while the pump is idle, automatically moving back as pressure builds up.

If no cistern water service is at all desired, then an abbreviated construction as shown in Figure 3 accomplishes automatic repriming, replacing water in pipes 10 and 14 from tank 5 until the normal discharge pressure is built up, after which valve 69 closes against any further flow.

The operation of the unit shown in Figure 2 is essentially the same as described for unit 15.

If desired, the final operating pressure may be made considerably less than 60 lbs. by adjustment of the different units.

I claim as new:

1. In an automatic cistern and well pumping plant, the combination of a suction type force pump, an electric motor operably connected to said pump, an electric power source, a well water tank, an electric switch connected to said tank and interposed between said motor and said power source, a cistern, a cistern water tank, a second electric switch, said switch being connected to said tank and interposed between said motor and said power source, a discharge chamber from said pump, an intake chamber to said pump, a passage from said discharge chamber to said well water tank, a pressure control valve connected into said passage, a jet type booster unit comprising a jet and conical delivery tube, a second discharge passage, said second passage extending from said discharge chamber to the jet of said booster unit, a pressure controlled check valve in said second passage, an automatic control unit comprising a diaphragm chamber, a diaphragm across said chamber, one side of said diaphragm chamber being connected to said discharge chamber, the opposite side of said diaphragm chamber being open to atmospheric pressure, a spring in this side of said chamber and disposed to support said diaphragm, an intake control chamber fixed to said diaphragm chamber, a passage connecting said intake control chamber to the intake chamber of said pump, a passage from said intake control chamber to the delivery tube of said booster jet unit, a valve controlling said passage, said valve being operably connected to said diaphragm, a second

passage from said intake control chamber, said second passage extending to said cistern, an automatic valve controlling said passage, said valve being operably connected to said diaphragm, a second and manually controlled valve in said passage, a passage from said pump discharge chamber to said cistern water tank, an automatic valve in said passage, said valve being operably connected to said diaphragm, a manually operable valve in said passage, a passage from said intake control chamber to said well water tank, a manually operable valve in said passage, an electric switch fixed to said diaphragm chamber, being operably connected to said diaphragm and interposed in series connection between said second switch and said power source.

2. In an automatic cistern and deep well pumping plant the combination of a suction type pump, means for operating said pump, a well, a cistern, a well water tank, a cistern water tank, a discharge chamber fixed to said pump, an intake chamber fixed to said pump, a passage from said discharge chamber to said well water tank, a pressure controlling valve connected into said passage, a jet type booster unit in said well, said unit comprising a cone shaped delivery tube and a jet disposed to discharge into its smaller end, a passage from said discharge chamber to said jet, a pressure operated check valve in said passage, an automatic master control unit, said unit comprising a diaphragm chamber, a diaphragm across said chamber, one side of said chamber being connected to said discharge chamber, the opposite side of said chamber being open to atmospheric pressure, a spring disposed in the open side of said chamber and disposed to support said diaphragm, an intake control chamber fixed to said diaphragm chamber, a passage extending from said intake control chamber to the intake chamber of said pump, a passage from said intake control chamber to said delivery tube of the booster unit, a valve controlling said passage, said valve being operably connected to said diaphragm, a cistern water intake passage extending from said intake control chamber, a valve in said passage, said valve being operably connected to said diaphragm, a passage from said pump discharge chamber to said cistern water tank, a valve in said passage, said valve being operably connected to said diaphragm.

3. In an automatically reprimed pumping plant, the combination of a suction type pump, means for operating said pump, a storage reservoir, a pump discharge chamber with passage from said chamber to said storage reservoir, a pressure control valve connected into said passage, an intake chamber fixed to said pump, an intake pipe extended downwardly from said intake chamber, an automatic repriming assembly comprising a passage from said intake chamber to said storage reservoir, a valve controlling said passage, a diaphragm chamber fixed to the housing of said valve, a diaphragm across said chamber, said diaphragm being operably connected to said valve, one side of said chamber being connected by a passage to said pump discharge chamber, the opposite side of said diaphragm chamber being open to atmospheric pressure, a spring disposed to move said diaphragm to normally maintain said valve in an open position when the pump is not delivering approximately its maximum pressure.

THADDEUS S. HARRIS.
